UNITED STATES PATENT OFFICE.

FANNIE DE GRAFF, OF ILWACO, WASHINGTON.

WAFFLE-IRON.

1,336,734.

Specification of Letters Patent. Patented Apr. 13, 1920.

Application filed April 19, 1919. Serial No. 291,256.

To all whom it may concern:

Be it known that I, FANNIE DE GRAFF, a citizen of the United States, residing at Ilwaco, in the county of Pacific and State 5 of Washington, have invented certain new and useful Improvements in Waffle-Irons, of which the following is a specification.

This invention relates to cooking utensils, and more particularly to waffle irons.

10 The primary object of the invention is to provide a frameless waffle iron which will rest flat on the top of the stove when in use and avoid the necessity of removing a lid to permit turning of the iron and to permit 15 the batter to cook evenly without the requirement of extreme heat.

Another object is to construct a waffle iron which is designed to be lifted bodily and turned with very little exertion.

20 With the foregoing and other objects in view, which will appear as the description proceeds, the invention resides in the combination and arrangement of parts and in the details of construction hereinafter described and claimed, it being understood that changes in the precise embodiment of 25 the invention herein disclosed may be made within the scope of what is claimed without departing from the spirit of the invention.

30 In the accompanying drawings:—

Figure 1 represents a top plan view of a waffle iron constructed in accordance with this invention and shown in closed position, parts of the handle being broken out,

35 Fig. 2 is a similar view with the iron shown open, and

Fig. 3 is an edge view with parts broken out.

In the embodiment illustrated, the waffle 40 iron 1 constituting this invention is composed of two coöperating sections 2 and 3, which may be of any desired configuration, being here shown circular. These sections 2 and 3 are hingedly connected at 4 and provided at diametrically opposite points with handles 5 riveted or otherwise rigidly secured thereto and which are preferably made about twelve or fourteen inches long, although obviously their length may be varied. These handles 5 are so arranged 45 that when the sections 2 and 3 are closed they will overlap as shown in Figs. 1 and 3, so that when grasped by the cook the sections will be held in closed position.

Each section has a batter chamber 6 surrounded by an upstanding flange 7 and having on its inner face a pattern in cameo, said pattern being of any desired configuration, here shown in the form of a star with diamond shaped elements 8 distributed there- 55 over.

Surrounding the batter chamber 6 is an extension trough 9, here shown annular which is designed to catch any batter overflowing from chamber 6 or which may be 60 dropped from the spoon while said chamber is being filled. This trough 9 has an upstanding flange 10 around its outer edge and when the sections 2 and 3 are closed the edges of these flanges abut as is shown 65 clearly in Fig. 3.

These sections are preferably made as light as possible and hence the preferred material is aluminum, although iron may be used and molded as thin as is possible so 70 that the irons may be readily lifted by the handles 5 for turning or transportation.

The outer flat faces of the sections 2 and 3 are designed to rest on the top of a stove in a manner similar to a frying pan but are 80 preferably provided with spacing ribs 11 so that the heat will be evenly distributed throughout chamber 6. The rib 11 here shown is in the form of a star, but obviously it need not necessarily be of this configura- 85 tion.

From the foregoing description, taken in connection with the accompanying drawings, the advantages of the construction and of the method of operation will be readily 90 apparent to those skilled in the art to which the invention appertains and while I have described the principle of operation of the invention together with the device which I now consider to be the best embodiment 95 thereof, I desire to have it understood that the device shown is merely illustrative and that such changes may be made as are within the scope of the claimed invention.

Having thus fully described my invention, what I claim as new and desire to secure by Letters Patent, is:—

A waffle iron comprising two members having up-standing side walls at the perimeter thereof, hingedly connected opposite the edges of said walls, each member being in the form of a unitary structure comprising a batter chamber proper with an upstand-

ing rib around its outer edge, a catch trough formed between said rib and said up-standing side walls of the member and surrounding said chamber on the inner face of said member, a spacing rib on the outer face of each of said members, the outer faces of said members being flat throughout their entire area except for said spacing rib to provide for the uniform spacing of all parts of the

outer face of the iron from its support to 10 insure uniform cooking of its contents.

In testimony whereof I affix my signature in presence of two witnesses.

MRS. FANNIE DE GRAFF.
